(57) **CLAIM**

The ornamental design for a spike for a loudspeaker, as shown and described.

DESCRIPTION

The patent or application file contains at least one drawing executed in color. Copies of this patent or patent application publication with color drawing(s) will be provided by the Office upon request and payment of the necessary fee.

Spike for a loudspeaker

1.1 is a side view of a spike for a loudspeaker showing the new design, the front, back, right and left side views being identical;

1.2 is a top view thereof;

1.3 is a bottom perspective view thereof;

1.4 is a bottom view thereof; and

1.5 is a top perspective view thereof.

The portion of the spike for a loudspeaker as shown in the color yellow forms no part of the claimed design.

The spike is for loudspeakers and other equipment to prevent vibrations.
